UNITED STATES PATENT OFFICE.

AUGUST KÜRTH, OF LEIPSIC, AND ROBERT BEYERMANN, OF GROSS BREITENBACH, GERMANY.

PROCESS OF PRODUCING COLORED PICTURES ON POTTERY AND PORCELAIN.

SPECIFICATION forming part of Letters Patent No. 297,608, dated April 29, 1884.

Application filed November 23, 1883. (No specimens.)

To all whom it may concern:

Be it known that we, AUGUST KÜRTH, of Leipsic, and ROBERT BEYERMANN, of Gross Breitenbach, Germany, citizens of Germany, 5 have invented a new and useful Improvement in the Process of Producing Colored Pictures on Pottery and Porcelain, of which the following is a specification.

Instead of painting the desired picture upon pottery or porcelain, the picture printed in colors upon paper is applied to the surface, after which the paper is removed and the colors remaining upon the article burned into the same in the well-known manner. By this 15 process the different colors forming the picture are very often more or less mixed or run into each other, and the desired picture loses its distinctness and sharp outlines.

To produce pictures upon pottery and porcelain perfectly sharp and clear is the nature 20 of our invention; and it consists in the use of the chromo-lithographic process for this purpose. We print the different colors forming the picture desired to be reproduced upon the 25 pottery or porcelain article separately, and apply the same, one after the other, to the article, and burn each color into the same before

a different color is applied, until the whole design or picture is completed.

According to the nature of the design or 30 of the nature of the colors themselves, two or more colors may sometimes be in this manner transferred to the surface of the article and burned into the same at the same time.

By this process we are able to reproduce 35 any design or colored picture upon pottery or porcelain without any intermixture of colors and with perfect sharp and distinct outlines.

We do not claim the process of transferring 40 colored pictures to the surface of pottery and porcelain; but

What we claim as our invention, and desire to secure by Letters Patent, is—

The application and use of the chromo-lithographic process for the reproduction of 45 colored pictures on pottery and porcelain, in the manner and for the purpose substantially as described.

AUGUST KÜRTH.
ROBERT BEYERMANN.
